ELECTRICAL SWITCH

Albert Henry Midgley, Moor Park, Northwood, England, assignor of one-half to Albert Morrell Midgley, Moor Park, Northwood, England

Application May 9, 1952, Serial No. 286,967

Claims priority, application Great Britain May 21, 1951

2 Claims. (Cl. 200—113)

1

This invention relates to electric switches. The invention consists of a snap-action electric switch having a switch member formed from a sheet of spring material which is firmly supported at one part leaving a strip separated from the supported part by a space and the length of which is increased slightly in relation to the supported part.

The invention further consists of a snap-action switch having a switch member formed from a sheet of spring material and having a slot therein to form two strips the length of one of which is increased slightly in relation to the other. The sheet may be supported at one end or at the side of the slot corresponding to the non-lengthened strip. The latter arrangement will give smaller movement and more precise control.

An example of the application of the invention is in connection with an interrupter switch of the kind in which a stretch wire when heated is adapted by a change of length to cause a contact operation by which the heating current is disconnected whereby the wire is cooled and by its resulting change of length, causes a further contact operation re-connecting the heating circuit.

Such switches may be used, for example, in connection with flashing signals for indicating that a motor vehicle is about to turn.

The invention further consists of an electric switch of the kind mentioned in which the sheet of spring material controls the opening and closing of at least two circuits.

Preferably, the additional circuit is one which does not include the heater wire and conveniently this circuit is opened and closed by a contact on a different part of the spring sheet to that which controls the circuit through the heated wire.

An embodiment of the invention will be described with reference to the accompanying drawings.

Figure 1 is a plan view.

Figure 2 is a section on the line 2—2 of Figure 4.

Figure 3 is a section on the line 3—3 of Figure 5.

Figure 4 is a section on the line 4—4 of Figure 2, and

Figure 5 is a section on the line 5—5 of Figure 1.

In the embodiment there are mounted on a circular disc 1 of insulating material, three terminal members 2, 3 and 4 which extend through the disc to which they are secured by bending

2

over tongues 2a, 3a, and 4a respectively and passing them back through the disc, and are connected with extension pieces extending at right angles to the disc on the other side.

5 The extension pieces 5 and 6 of the terminal members 2 and 3 respectively are separated by a sheet of insulating material 8 and a piece of Phosphor bronze spring sheet 9, these parts being secured together by two hollow rivets 10 extending therethrough with an insulating collar 11 around the head of each.

An insulating former 11' is held in position by two limbs 11'a which extend through the hollow rivets 10.

15 One extension piece 6 (the one insulated from the rivets by the insulating collar and against which the spring sheet 9 rests), carries a spring-loaded screw 12 extending through a tongue 6a bent away from the spring sheet. The other extension piece 5 of the terminal 2 carries a contact member 5a on its inner side facing the end of the screw.

It is also formed with two upwardly turned arms 5b and 5c and a screw 7 is in threaded engagement through the arm 5c and with its end abutting against the arm 5b.

20 The spring sheet 9 is firmly supported at one part 9a leaving a strip 9b separated from the supported part by a slot 9c, the length of the strip 9b being increased slightly in relation to the supported part 9a as by hammering.

A stretched wire 13 lies generally over the slot and is secured at one end to a bent-over ear 14a on a T-piece 14 fitted in one end of the spring sheet 9 which end is slotted to hold the T-piece.

25 The wire is formed through a bead 5b' in a hole in the arm 5b and after being wound around the insulating former 11' is returned to the ear 5c' on the arm 5c.

30 The end of the spring sheet 9 remote from the end to which the wire 13 is secured, is bent to bias the unsupported strip 9b so that contact piece 9d therein is in contact with the contact member 5a on the extension piece 5 before the wire is tightened in which position the circuit between the terminals 2 and 3 does not extend through the wire 13.

35 The spring sheet 9 is also formed with a tongue 9d parallel to the strip 9b, and which is bent adjacent its free end first at right angles away from the side of the sheet in which the wire is located and then back again in the opposite direction at right angles to lie parallel with the sheet again.

40 A further extension piece 15 is secured to the

disc by the terminal 4 to extend at right angles to the tongue 9d and to come to lie with its free end adjacent the free end of the tongue and between the tongue and the rest of the spring sheet of which the tongue forms part and contact pieces 16, 17 are provided at the free ends of the tongue and further strip on the sides facing each other.

The contacts 16, 17 of the tongue 9d and strip 15 respectively will alternately open and close a circuit extending from the two terminals 3 and 4, connected respectively to the spring sheet 9, and the strip 15, which circuit does not pass through the wire 13.

This circuit is conveniently used for flashing, say, a warning light inside a car while the circuit which includes the wire is flashing a turning signal light on the outside of the car.

When the wire 13 is tightened up, by means of the screw 1 extending between the two frames in said other extension piece, the unsupported strip 9b will be snapped over into contact with the end of the spring-loaded screw 12 in which position the circuit between the two terminals 2 and 3 extends through the wire 13.

Adjustment of the spring-loaded screw 12 will control the rate of interruption of the circuit between the terminals and through the wire and adjustment of the other screw 1 will control the relation of the periods during which the circuit is made and the periods during which it is broken.

It will be understood that the supported part of the spring sheet need not be a continuous strip in which case the lengthening of the unsupported part would be effected after the riveting in position.

Various other modifications may be made within the scope of the invention.

I claim:

1. An electric interrupter switch comprising a pair of terminal members, a sheet of spring material firmly supported at one part between the terminal members leaving a strip separated from the supported part by a slot, the length of which strip is increased slightly in relation to the supported part, an insulating layer between one terminal member, and the sheet of spring material, a stop member on the other terminal member and located opposite the centre part of the strip, a stretched wire secured at one end to one end of the sheet of spring material and at the other end to said one of the terminal members and adapted when cold to force the centre part of the strip into contact with said stop member to complete a circuit between said terminal members through the wire, and when hot to allow the centre part of the strip to move away from said contact member and thereby interrupting said circuit through the wire.

2. An electric interrupter switch as claimed in claim 1, comprising a third terminal member and a tongue on the sheet of spring material adapted to contact said terminal member in one position of the strip and to be separated therefrom in the other position of the strip.
